(57) **CLAIM**

The ornamental design for hydrotherapy jet escutcheon, as shown and described.

DESCRIPTION

FIG. 1 is a perspective view of the hydrotherapy jet escutcheon.

FIG. 2 is a top view of the hydrotherapy jet escutcheon.

FIG. 3 is a first side view of the hydrotherapy jet escutcheon; and,

FIG. 4 is a section view of FIG. 2 of the hydrotherapy jet escutcheon.

The dashed line immediately adjacent the claimed areas in FIG. 4 represent the boundaries of the claimed design. None of the broken lines form any part of the claimed design.
